UNITED STATES PATENT OFFICE.

JOHN B. CARROLL, OF CHICAGO, ILLINOIS.

SCISSORS-SHARPENER.

No. 901,522.

Specification of Letters Patent.

Patented Oct. 20, 1908.

Application filed August 2, 1907. Serial No. 386,743.

To all whom it may concern:

Be it known that I, JOHN B. CARROLL, a citizen of the United States, residing at Chicago, in the county of Cook and State of Illinois, have invented certain new and useful Improvements in Scissors - Sharpeners, of which the following is a specification.

This invention is a scissors - sharpener, which can be cheaply produced and is suitable for mailing.

The sharpening device is a hard steel wire or strip, preferably secured at or near the margin of the card, a portion of the body of the card adjacent to the wire being cut away to provide an opening to receive one blade of the scissors.

Referring to the accompanying drawing:— Figure 1 is an elevation of one side of the card, showing the wire secured in place by a sheet-metal fastener, and Fig. 2 is an elevation of the other side of the card, showing the ends of the wire-fastener unfolded.

A rectangular card 1 is illustrated, having an opening 2 to receive one blade of the scissors. The wire 3 of hard steel is secured above and extends across the opening, lying in recesses 4 in the edge of the card. A sheet-metal wire-fastener and guard 5 is secured on one face of the card by means of a rivet 6 and its ends 5' are folded around the wire and down upon the other face of the card. The inner

edge of this fastener is flush with the edge of the card-opening 2 and protects the card from injury by the scissors-blade, and serves to reinforce and stiffen the same.

Advertising matter may be printed on both faces of the card and it may be transmitted through the mails without injury to other matter, having no projecting metal points.

I claim:

1. A scissors-sharpener, comprising a card having a marginal opening, a hard metal strip extending across said opening and seated against the edge of the card, and a sheet-metal fastener secured to the card and bent around the strip.

2. A scissors-sharpener, comprising a card having a marginal opening and a recess at each side of the opening, a hard metal strip extending across said opening and seated in said recesses, and a sheet-metal fastener and guard secured to the card around the opening and having its ends bent around the strip.

In testimony whereof, I affix my signature in presence of two witnesses.

JOHN B. CARROLL.
